SPARKLER TOY

Perry Feuer, Roslyn, N.Y., assignor to Creative Creations, Inc., New York, N.Y.

Filed Jan. 8, 1971, Ser. No. 105,145

Term of patent 14 years

Int. Cl. D21—01

U.S. Cl. D34—15

FIG. 1 is a front elevation of a sparkler toy showing my new design;

FIG. 2 is a right side elevational view thereof;

FIG. 3 is a rear elevational view thereof;

FIG. 4 is a left side elevational view thereof;

FIG. 5 is a top view of the design; and

FIG. 6 is a bottom view of the design.

I claim:

The ornamental design for a sparkler toy, as shown.
